UNITED STATES PATENT OFFICE.

JULIUS O. BAKKE, OF MINNEAPOLIS, MINNESOTA, ASSIGNOR TO WASHBURN-CROSBY COMPANY, OF MINNEAPOLIS, MINNESOTA, A CORPORATION OF MINNESOTA.

THREAD-CUTTER FOR BAG-SEWING MACHINES.

1,342,150.

Specification of Letters Patent.

Patented June 1, 1920.

Application filed August 5, 1915. Serial No. 43,740.

To all whom it may concern:

Be it known that I, JULIUS O. BAKKE, a citizen of the United States, and resident of Minneapolis, in the county of Hennepin 5 and State of Minnesota, have invented certain new and useful Improvements in Thread-Cutters for Bag-Sewing Machines, of which the following is a specification.

This invention relates to improvements 10 in thread-cutting mechanism for sewing machines, and more particularly has reference to such mechanism as applied to machines for sewing filled bags, as those in which flour and similar materials are packed.

More specifically stated, the present invention is designed as an improvement on the construction of thread cutter illustrated and described in United States Letters Patent No. 768,111, Burghardt, dated August 23, 1904. That construction has proved practical for the purposes intended, but the cutter blades are so exposed that unless great care is exercised by operatives of the 25 machine equipped therewith there is possibility of injury to the operatives. Moreover, the position of the Burghardt cutter in relation to the sewing mechanism is somewhat remote therefrom, the point of severance of the thread being such that a considerable length of the chain of stitches remains at the marginal portions of the bags after the chain is cut. This involves material waste of thread. The present invention, therefore, has as its primary object to provide a construction of thread-cutting mechanism which shall be safer to operate than that of the Burghardt patent, thereby insuring to the operatives freedom from injury by the cutters; and furthermore, to effect such a reorganization of the cutting mechanism with relation to the sewing mechanism as will obviate a waste of thread when the chain of stitches is severed. This 40 avoids protruding ends of any considerable length at the bag margins and imparts to the closed mouths of the packages a neat appearance when sewed.

The invention further aims to provide 50 cutting mechanism of the class mentioned

which is simple and highly efficient, light in construction, and one which can be maintained easily in proper working condition.

Having these general objects in view, and others which will appear as the nature of 55 the improvements is better understood, the invention consists substantially in the novel construction, combination and arrangement of parts hereinafter fully described, illustrated in the accompanying drawings, and 60 pointed out in the appended claims.

In the drawings—

Figure 1 is a side elevation of a bag-sewing machine equipped with thread-cutting mechanism constructed in accordance with 65 the present invention, only those portions of the sewing machine being illustrated as are necessary for an understanding of the invention.

Fig. 2 is a sectional plan view on the line 70 2—2 of Fig. 1.

Fig. 3 is a detail elevation of the needle plate of the sewing mechanism.

Fig. 4 is a view in elevation, similar to Fig. 1, observing the sewing mechanism at 75 the side opposite to that seen in Fig. 1, parts being illustrated in section.

Fig. 5 is a view similar to Fig. 4, the cutting mechanism being illustrated as closed or in the condition it assumes for severing 80 the thread.

Fig. 6 is an enlarged detail sectional view of the cutter-supporting head and the cutters associated therewith.

Fig. 7 is a vertical sectional view of the 85 cutter-supporting head, the line of section being through the pivotal point of the cutter blades.

Referring now in detail to the accompanying drawings, the numeral 1 designates 90 a sewing head, which may be of any approved construction, the same being disposed so that its needle bar 2 operates in a horizontal plane. This head includes the usual presser-foot 3 which coöperates with 95 the needle plate 4 wherein is provided a slot 5 for accommodating the usual feeding mechanism.

As before stated, the present invention is 100 designed as an improvement upon the con-

struction of thread cutter illustrated in the Burghardt Patent, No. 768,111. This construction includes a drive shaft 6 at the upper end of which is located a pulley 7 having a belt 8 for transmitting motion to the driving mechanism 9 of the sewing head. Reference is to be made to the Burghardt patent for a more complete understanding of the specific driving mechanism included therein. For the purposes of the present invention it is but necessary to state that the drive shaft 6 at its lower end is provided with a suitable clutch by which rotation may be imparted to the shaft 6 when it is desired to actuate the sewing head 1. As illustrated in the Burghardt patent, the thread-cutting mechanism is rendered inoperative while the sewing head is being actuated, and when the sewing operation is complete the sewing mechanism comes to rest and the thread-cutting mechanism is immediately set in motion. The conditions of operation of the thread cutter in the present instance are the same as those just referred to, a connecting rod 10 being interposed between the clutch at the lower end of the drive shaft 6 and a contact arm 11 by means of which the thread-cutting mechanism becomes operative. As is disclosed in the Burghardt patent, the contact arm 11 is sleeved upon a collar 12 forming part of the cone member 13 of a clutch, a set screw 14, or its equivalent, being employed for holding the contact arm 11 in tight engagement with the collar 12. The collar 12, and perforce, the cone member 13, are free to slide longitudinally of the drive shaft 6. Upon the latter is mounted the other member 15 of the clutch, said member 15 being tightly engaged with the drive shaft 6 by a set screw 16, or its equivalent. As also clearly appears from the disclosure of the Burghardt patent, when the power clutch at the lower end of the drive shaft 6 is operated to remove the power from said shaft, the clutch member 13 is brought into engagement with the clutch member 15 by the connecting rod 10. But as the shaft 6 continues to operate under its momentum the engagement of the member 15 with the member 13 causes the latter to rotate, and this results in the swinging of the contact arm 11 in the direction of the arrow illustrated in Fig. 2.

The present invention seeks to provide an improved form of thread-cutting mechanism with a view to overcoming the objectionable features of the thread-cutting mechanism of the Burghardt patent. Therefore, a radical departure is made in the construction of the cutting members and the manner in which the latter act upon the chain of stitches. To this end a cutter-supporting head 17 is employed, which head is substantially L-shaped, one end thereof being pro-

vided with a bore 18 of suitable configuration, and the other end being slotted, as at 19, in order to receive and house a pair of cutter blades 20. These blades 20 are provided with shear members 21 which coöperate with each other in a scissors-like fashion, the blades 20 being pivoted in the slot 19 by means of a screw 22 having adjacent to its head a coil spring 23 whereby to exert the requisite tension upon the cutter blades. 70 The shear members 21 are retained normally in open or separated position through the medium of a spring 24 the ends of which are connected to the upper ends of the cutter blades 20. The tendency of this spring 24 80 is to draw the ends of the blades 20 toward each other, and in order to limit this relative movement of said blades a stop 25 is arranged transversely of the slot 19 against which the blades are designed to contact 85 under the influence of the spring 24. This limits the opening or separating movement of the shear members 21 and insures their entrance into the slot 26 when moved therein. For automatically closing these members a vertically-disposed slot 26 is formed in the needle plate 4 of the sewing head, said slot being directly opposite the shear members 21, and at a predetermined time said members 21 are introduced into said slot. 90 The upper and lower ends of said slot are beveled, as at 27, said beveled ends coöperating with the rounded outer edges of the shear members, and as the latter are forced into the slot 26 it is apparent that the beveled ends of said slot force the shear members together and cause the latter to sever the chain of stitches. It will be observed that the shear members 21 are arranged at one side of the line of seam and the needle 100 plate 4 with its slot 27 occupies a position at the opposite side thereof. The shear members travel across the line of the seam and project away from the position normally occupied by the machine operator, so that in 105 performing the cutting operation the shear members are moved away from the operator. This reduces liability of injury to the operator to a minimum.

A U-shaped actuator 28 is employed for 115 imparting motion to the cutter-supporting head. One leg of this actuator is longer than the other, the actuator being mounted for reciprocation in the standard 29 of the sewing machine. The free end of the longer 120 leg 30 of the actuator is received by the bore 18 of the head 17, said head being adjustably mounted upon the leg 30 by means of set screws 31, or their equivalent. The shorter leg 32 is encircled by a coil spring 125 33 which is interposed between the standard 29 and a washer 34 at the free end of said leg. When, therefore, movement is imparted to the actuator 28 for closing the shear members 21, the spring 33 becomes com- 130

pressed and upon proper release of the actuator 28 in the manner hereinafter described the spring 33 exerts its force to project the actuator 28 in an outward direction 5 and thereby to withdraw the shear members 21 from the slot 26 of the needle plate.

Extending rearwardly from the standard 29 is a supporting bar 35 to which bar an operating lever 36 is pivoted, as at 37. 10 Interposed between the upper end of said lever 36 and the actuator is a link 38 whereby movement is imparted to the actuator from the lever 36. The lower end of said lever 36 extends into the path of movement 15 of the contact arm 11 and as the latter swings in the direction indicated by the arrow in Fig. 2 it engages the lever 36 and thereby operates the actuator 28 for introducing the shear members 21 into the slot 26. The reverse movement of the contact arm 11 is limited by a depending stop 39, said stop being carried by the bar 35.

If it be desired to cushion the movement of the cutter-supporting head 17 a washer 25 40 of suitable material may surround the leg 30 of the actuator 28 at a point between the cutter-supporting head and the sewing head.

From the foregoing description the operation 30 of the herein-described cutter will be apparent, and briefly stated is as follows:

Assuming that the bag mouth has been closed by the sewing mechanism and the 35 power clutch operated to disengage the same from the shaft 6, the contact arm 11 is actuated in the manner previously set forth herein and thereby is brought into engagement with the lower end of the lever 36. This lever is thus swung upon its fulcrum and the actuator 28 is drawn rearwardly compressing the spring 33 and forcing the shear members 21 into the slot 26. The members 21 thus move toward each 40 other and sever the chain of stitches, which latter, in the passage of the bags through the machine, lie in front of the needle plate 4 and between said shear members. As the shear members 21 close upon each other the spring 24 becomes tensioned. The chain of stitches having been 45 severed the shear members are now free to recede from the slot 26; and in the expansion of the spring 33 the actuator moves in the opposite direction thereby withdrawing the shear members from said slot. This 50 movement of the actuator 28 shifts the position of the lever 36, and the contact arm 11 moves in a reverse direction to that 55 which it follows under the momentum of the drive shaft 6. Its reverse movement, however, is limited by its contact with the depending stop 39. When the position of the parts has been restored in the manner 60 just described the sewing mechanism again

may be put in operation for closing the mouth of the following bag, and when this has been effected the chain of stitches may be severed as specified. The periodic operation of the cutter will continue so long as 70 the bags are passed through the sewing machine.

Having thus described the invention, what is claimed as new, and desired to be secured by Letters Patent, is:

75

1. A thread cutter of the class described, comprising a plurality of cutters mounted for relative movement, an element arranged in juxtaposition to said cutters and provided with a slot into which the cutters are 80 introduced and which cooperates with said cutters to effect the cutting operation, and means for establishing relative movement between said cutters and said element whereby to introduce the cutters to and remove the same from said slot.

2. A thread cutter of the class described, comprising a plurality of pivoted cutters, an element arranged in juxtaposition to said cutters and provided with a slot into which 90 the cutters are introduced and which cooperates with said cutters to effect the cutting operation, and means for establishing relative movement between said cutters and said element whereby to introduce the cutters to and remove the same from said slot.

3. A thread cutter of the class described, comprising a plurality of pivoted cutters, an element arranged in juxtaposition to said cutters and provided with a slot into which 100 the cutters are introduced and which cooperates with said cutters to effect the cutting operation, means for establishing relative movement between said cutters and said element whereby to introduce the cutters to and remove the same from said slot, and 105 means for actuating said cutters to open the same when released from said slot.

4. A thread cutter of the class described, comprising a plurality of pivoted cutters, an element arranged in juxtaposition to said cutters and provided with a slot into which the cutters are introduced and which cooperates with said cutters to effect the cutting operation, means for establishing relative movement between said cutters and said element whereby to introduce the cutters to and remove the same from said slot, 110 means for opening the cutters when the latter are released from said slot, and means 115 for limiting the degree of separation of the cutters.

5. A thread cutter of the class described, comprising a cutter support, a plurality of cutters associated therewith and mounted 120 for relative movement, a stationary element arranged in juxtaposition to said cutter support and provided with a slot into which the cutters are introduced and which cooperates with said cutters to effect the cut- 125

130

ting operation, and means for establishing relative movement between said cutter support and said element whereby to introduce the cutters to and remove the same from 5 said slot.

6. A thread cutter of the class described, comprising a cutter support, a plurality of cutters associated therewith and mounted for relative movement, a stationary element 10 arranged in juxtaposition to said cutter support and provided with a slot into which the cutters are introduced and which co-operates with said cutters to effect the cutting operation, means for establishing relative movement between said cutter support and said element whereby to introduce the cutters to and remove the same from said 15 slot, and means for actuating the cutters to open the same after their removal from said 20 slot.

7. A thread cutter of the class described comprising a slotted cutter support, a plurality of cutters arranged within the slot of said support and pivotally mounted there- 25 in, a slotted element arranged in juxtaposition to the cutter support and adapted to receive said cutters for effecting the cutting operation, and means for effecting relative movement between said slotted element and 30 the cutter support.

8. A thread cutter of the class described comprising a slotted cutter support, a plurality of cutters arranged within the slot of said support and pivotally mounted there- 35 in, a slotted element arranged in juxtaposition to the cutter support and adapted to receive said cutters for effecting the cutting operation, means for effecting relative movement between said slotted element and the 40 cutter support, and means for opening said cutters when the latter are removed from said slotted element.

9. A thread cutter of the class described comprising a plurality of pivoted cutters, a 45 slotted element arranged in juxtaposition to said cutters and provided with beveled portions for co-operation with said cutters to close the latter, means for introducing said cutters into said slotted element, and means 50 for removing said cutters therefrom.

10. A thread cutter of the class described, comprising a plurality of cutter members, a stationary element arranged in juxtaposition to said cutters and co-operating with the 55 latter for closing the same, means for moving the cutters into co-operative relation with said stationary element for closing the cutters and effecting the cutting operation, and means for releasing the cutters from co- 60 operative relation with said stationary element.

11. A thread cutter of the class described, comprising a plurality of pivoted cutters, a stationary element arranged in juxtaposition to said cutters and co-operating with 65

the latter for closing the same, means for moving said cutters into co-operative relation with said stationary element to close the cutters and effect the cutting operation, means for removing the cutters from coö- 70 perative relation with said stationary element, and means for restoring the cutters to open position when released from coöperative relation with the stationary element.

12. A thread cutter of the class described, 75 comprising a plurality of cutters, means arranged in juxtaposition thereto and coöperating with the cutters to effect the cutting operation, positively-acting means for moving the cutters into coöperative relation 80 with said coöperating means, and resilient means for restoring the cutters to non-cutting position.

13. A thread cutter of the class described, comprising a plurality of cutters, means co- 85 operating therewith for actuating the cutters to effect the cutting operation, positively-acting means for moving the cutters into coöperative relation with said cutter-actuating means, and resilient means for re- 90 leasing the cutters from coöperative relation with said actuating means.

14. A thread cutter of the class described, comprising a plurality of pivoted cutters, means for actuating the latter to effect the 95 cutting operation, positively-driven means for moving the cutters into coöperative relation with said actuating means, means acting in opposition to said positively-driven means for releasing said cutters from coö- 100 perative relation with said actuating means, and means for restoring the cutters to non-cutting position when released from said actuating means.

15. A thread cutter of the class described, 105 comprising a plurality of pivoted cutters, a slotted element arranged in juxtaposition to said cutters and coöperating with the latter for effecting the cutting operation, posi- 110 tively-driven means for introducing the cutters into said slotted element, and means acting in opposition to said positively-driven means for removing the cutters from said slotted element.

16. A thread cutter of the class described, 115 comprising a plurality of pivoted cutters, a slotted element arranged in juxtaposition to said cutters and coöperating with the latter for effecting the cutting operation, posi- 120 tively driven means for introducing the cutters into said slotted element, means acting in opposition to said positively-driven means for removing the cutters from said slotted element, and means for restoring the cutters to non-cutting position when re- 125 leased from said slotted element.

17. A thread cutter of the class described, comprising cutting mechanism, actuating means adapted to receive and with which the cutting mechanism is engaged to effect 130

the cutting operation, said cutting mechanism being removable from engagement with said actuating means, an actuator for establishing movement between the cutting mechanism and said actuating means, and means for restoring said cutting mechanism to non-cutting position when removed from said actuating means.

18. A thread cutter of the class described, comprising cutting mechanism, actuating means adapted to receive and with which the cutting mechanism is engaged to effect the cutting operation, said cutting mechanism being removable from engagement with said actuating means, an actuator for establishing movement between the cutting mechanism and said actuating means, means for positively operating the actuator to effect the cutting operation, means acting in opposition to said positively-acting means for moving the actuator to disengage the cutting mechanism from its actuating means, and means for restoring said cutting mechanism to non-cutting position when removed from said actuating means.

19. A thread cutter of the class described, comprising a plurality of pivoted cutters, a slotted element arranged in juxtaposition to said cutters and coöperating with the latter for effecting the cutting operation, an actuator to which said pivoted cutters are connected and adapted to establish relative movement between said cutters and said slotted element, positively-acting means for operating the actuator to introduce the cutters to said slotted element, and means acting in opposition to said positively-acting means for operating the actuator to release the cutters from said slotted element.

20. A thread cutter of the class described, comprising a plurality of pivoted cutters, a slotted element arranged in juxtaposition to said cutters and coöperating with the latter for effecting the cutting operation, an actuator to which said pivoted cutters are connected and adapted to establish relative movement between said cutters and said slotted element, positively-acting means for operating the actuator to introduce the cutters to said slotted element, means acting in opposition to said positively-acting means for operating the actuator to release the cutters from said slotted element, and means for restoring the cutters to non-cutting position when so released.

21. A thread cutter of the class described, comprising a plurality of cutters, a reciprocating actuator to which said cutters are connected, means adjacent to said cutters adapted to coöperate therewith for effecting the cutting operation, positively-acting means for moving the actuator in one direction to establish coöperative relation between the cutters and said actuating means, and means for moving the actuator in the

opposite direction to release the cutters from coöperative relation with said actuating means.

22. A thread cutter of the class described, comprising a U-shaped actuator, cutting mechanism carried by one leg thereof, means coöperating with said cutting mechanism to effect the cutting operation, means for moving the actuator to establish the coöperative relation between said cutting mechanism and said actuating means, and means carried by the other leg of the actuator for operating the latter to release the cutting mechanism from its coöperative relation with said actuating means.

23. A thread cutter of the class described, comprising a U-shaped actuator mounted for reciprocatory movement, cutting mechanism carried by one leg of said actuator, means adapted to coöperate with said cutting mechanism to effect the cutting operation, means for moving the actuator in one direction to establish coöperative relation between said cutting mechanism and said actuating means, and means associated with the other leg of said actuator for moving the latter in the opposite direction to release the cutting mechanism from coöperative relation with said actuating means.

24. A thread cutter of the class described, comprising a slotted cutter support, a plurality of cutters mounted for relative movement within the slot of said support, means arranged in juxtaposition to said support and coöperating with the cutters to effect the cutting operation, means for establishing relative movement between the cutter support and said actuating means, and a spring for restoring the cutters to non-cutting position when released from coöperative relation with said actuating means.

25. A thread cutter of the class described, comprising a slotted cutter support, a plurality of cutter blades pivotally mounted within the slot of said support, a slotted element arranged in juxtaposition to said cutter support and coöperating with said cutter blades to effect the cutting operation, means for establishing relative movement between said cutter support and said slotted element, a spring connected to said cutter blades for restoring the latter to non-cutting position when released from coöperative relation with said slotted element, and a stop arranged between said blades for limiting the degree of movement thereof when moving to non-cutting position.

26. In a sewing machine, the combination with the sewing head thereof and the needle plate associated therewith, said needle plate being provided with a slot, of cutting mechanism associated with said sewing head and adapted to coöperate with the slot of said needle plate to cut the line of stitches, and means for effecting relative movement be-

tween said cutting mechanism and the slotted needle plate.

27. In a sewing machine, the combination with the sewing head thereof and the needle plate associated therewith, said needle plate being provided with a slot, of a plurality of cutters mounted for relative movement with respect to said needle plate and across the line of stitches, said needle plate co-operating with said cutters to effect the cutting operation when the cutters are introduced into the slot thereof, and means for actuating said cutters toward and from said needle plate.

15 28. In a sewing machine, the combination with the sewing head thereof and the needle plate associated therewith, said needle plate being provided with a slot, of a plurality of pivoted cutters arranged adjacent to said slot and mounted for movement relative thereto, means for introducing said cutters into said slot for effecting the cutting operation, means for moving the cutters from said slot, and means for restoring the cutters to non-cutting position when removed from said slot.

29. In a sewing machine, the combination with the sewing head thereof and the needle plate associated therewith, said plate being provided with a slot, of a cutter support arranged adjacent to said needle plate, a plurality of pivoted cutters carried by said cutter support, said needle plate co-operat-

ing with said cutters to effect the cutting operation when the cutters are introduced 35 into said slot, means for establishing relative movement between the cutter support and said needle plate, and means for restoring the cutters to non-cutting position when the same are removed from said slot. 40

30. In a sewing machine, the combination with the sewing head thereof, of cutting mechanism arranged at one side of the line of the seam, means for moving said cutting mechanism across the line of the seam, and 45 means arranged at the opposite side of the line of the seam and with which said cutting mechanism co-operates for actuating the cutting mechanism to cut the chain of stitches. 50

31. In a sewing machine, the combination with the sewing head thereof, of a cutter support arranged at one side of the line of the seam, a plurality of cutters mounted in said support, means for moving said cutter 55 support across the line of the seam, and a slotted element arranged at the opposite side of the line of the seam, the slot of said element being adapted to receive said cutters for actuating the latter to cut the chain 60 of stitches.
